UNITED STATES PATENT OFFICE

156,956

DISPLAY RACK OR SIMILAR ARTICLE

Winfield S. Hassler, Chicago, Ill., assignor to The Curtiss Candy Company, Chicago, Ill., a corporation of Illinois

Application August 16, 1947, Serial No. 140,923

Term of patent 14 years

(Cl. D80—9)

To all whom it may concern:

Be it known that I, Winfield Scott Hassler, a citizen of the United States of America and resident of Chicago, county of Cook, and State of Illinois, have invented a new, original, and ornamental Design for Display Racks or similar articles, of which the following is a specification, reference being had to the accompanying drawings, forming a part thereof, wherein:

Figure 1 is a perspective view of a display rack or similar article, embodying my new design.

Fig. 2 is a front view thereof.

Fig. 3 is a side view thereof.

Fig. 4 is a top view thereof.

The broken lines showing the insert card are for illustrative purposes only.

The dominant features of my design reside in the portion shown in full lines.

What I claim is:

The ornamental design for a display rack or similar article, substantially as shown and described.

WINFIELD SCOTT HASSLER.
